(57) **CLAIM**

The ornamental design for the fan with stand, as shown and described herein.

DESCRIPTION

FIG. 1 is a front view of a fan with stand showing my new design;

FIG. 2 is a rear view of the fan with stand shown in FIG. 1; FIG. 3 is a left side view of the fan with stand shown in FIG. 1;

FIG. 4 is a right side view of the fan with stand shown in FIG. 1;

FIG. 5 is a top view of the fan with stand shown in FIG. 1; FIG. 6 is a bottom view of the fan with stand shown in FIG. 1;

FIG. 7 is a front perspective view of the fan with stand shown in FIG. 1;

FIG. 8 is a rear enlarged detail view of the top portion of the fan with stand shown in FIG. 1;

FIG. 9 is a front enlarged detail view of the top portion of the fan with stand shown in FIG. 1; and,

FIG. 10 is a front enlarged detail view of the top right side of the fan with stand shown in FIG. 1.

The broken lines in the drawings depict parts of the fan with stand that form no part of the claimed design.
